(57) **CLAIM**

The ornamental design for a coaxial cable port terminator, as shown and described.

DESCRIPTION

FIG. 1 is a perspective view of a coaxial cable port terminator showing my new design;

FIG. 2 is a top plan view thereof, the claimed portion of which is a mirror image to a bottom plan view;

FIG. 3 is a left side elevation view thereof, the claimed portion of which is a mirror image to a right side elevation view;

FIG. 4 is a front elevation view thereof; and,

FIG. 5 is a back elevation view thereof.

The broken lines shown represent unclaimed subject matter and form no part of the claimed design.
